His Attorney.

UNITED STATES PATENT OFFICE

2,193,699

SELF-LOCKING HANGER

Benjamin H. Sadler, Fairfield, Ala.

Application December 14, 1938, Serial No. 245,802

1 Claim. (Cl. 248—200)

This invention relates to an improved mounting for fire extinguishers and aims to provide safety means whereby once a fire extinguisher has been removed from its mounting it cannot again be placed thereon except by an authorized person.

The improved device includes a fire extinguisher supporting means which automatically moves to non-supporting position and is locked therein upon removal of the fire extinguisher.

10 The above and more detailed features of the invention will be fully apparent from the following specification, when read in connection with the accompanying drawing, in which:

Figure 1 is a front elevation with portions broken away showing the improved hanger supporting a fire extinguisher in position to be used;

Figure 2 is a side elevation thereof; and

Figures 3 and 4 are views similar to Figures 1 and 2 but showing the position of the parts after removal of the fire extinguisher.

20 Referring in detail to the drawing, 10 represents a base plate having guides 12 and 14 for slidably positioning a slide member 16 which is provided at its lower extremity with a supporting shelf or hook 18 adapted to support a fire extinguisher, indicated at 20.

A spring 22 has one end secured to a stud 24 carried by the slide 16 and its other end secured to a fixed anchorage pin 26 carried by the base plate 10 and projecting through a slot 28 formed in the slide.

25 A cover 30 encloses the slide and serves to prevent unauthorized persons from gaining access to locking mechanism to be presently described. Enclosed by the cover 30 there is a locking mechanism which is effective to prevent unauthorized persons from moving the supporting slide from the position of Figures 3 and 4 to that of Figures 1 and 2. The locking means illustrated includes 30 a latch dog 32 which is pivoted at 34 and normally pressed toward the edge of the slide 16 by a spring 36. The dog has an outwardly bent lip 38 at its free end for coaction with a locking notch 40 formed in the slide. Coincident with 35 the pivotal axis 34 and secured to the dog there is a sleeve-like member having recessed portions

adapted to cooperate with a suitable key which may be inserted through a keyhole 39 formed in the casing.

While the drawing shows one known type of small fire extinguisher resting bodily on the shelf 18 or hook 18, it is clear that a much larger extinguisher, generally known as the soda-acid type, can be hung vertically therefrom by engaging the handle thereof with said hook 18.

With the apparatus described it will be apparent that when the fire extinguisher 20 is removed from the supporting portion 18, the spring 22 will retract the slide and thus move the supporting portion 18 to the position of Figure 4 wherein it is apparent that it is inaccessible. The 15 slide will be locked in this position by the dog 32 and it cannot be again moved to a position to receive a fire extinguisher until an authorized person in possession of the key unlocks the dog and moves the slide to the position of Figures 20 1 and 2.

While I have described quite specifically the embodiment of the invention herein illustrated, it is to be understood that various modifications may be made by those skilled in the art without 25 departure from the invention, as defined in the appended claim.

I claim:

A device of the character described comprising a base plate, a slide guided thereby having a fire extinguisher supporting portion, a cover secured to the base plate, a spring tending to move the slide to non-supporting position, a pivotally mounted spring pressed dog effective in the retracted position of the slide to hold the supporting portion thereof in a position in which access thereto is prevented by said cover, said dog having a key engaging portion, said cover having an aperture aligned therewith, said slide being a one-piece flat element with an angularly bent 40 extremity to form said supporting portion, and said base plate being a single flat member and having integral guides bent into overlapping relation with said slide.
